ATTORNEYS

UNITED STATES PATENT OFFICE.

JAMES J. CURTIS, OF NEW YORK, N. Y.

QUOIN.

Application filed March 28, 1924. Serial No. 702,695.

To all whom it may concern:

Be it known that I, JAMES J. CURTIS, a citizen of the United States, and a resident of the city of New York, borough of Manhattan, in the county and State of New York, have invented a new and Improved Quoin, of which the following is a full, clear, and exact description.

This invention relates to quoins and has 10 for an object to provide an improved quoin wherein means are provided at each end of a pair of quoins which may be moved for locking the quoins in any adjusted position.

Another object in view is to provide a 15 quoin provided with means for gripping the bead of the co-acting quoin for locking the respective quoins against accidental shifting.

A further object is to provide an improved construction over the construction 20 shown in my application, Serial No. 637,546.

In the accompanying drawing—

Figure 1 is a side view of a pair of quoins disclosing an embodiment of the invention.

25 Figure 2 is a top plan view of one of the quoins shown in Figure 1, part being broken away at one end.

Figure 3 is a sectional view through Figure 1, approximately on line 3—3.

30 Figure 4 is a view similar to Figure 3 but showing a slightly modified construction.

Figure 5 is a view similar to Figure 4 but showing a further modified form of the invention.

35 Referring to the accompanying drawing by numerals, 1 and 2 indicate the two co-acting quoins, which quoins are provided with the usual teeth 3 and 4 for receiving a turning instrument. Also each quoin is provided with an inclined bead 5 and with 40 upstanding walls 6 and 7. In one of these walls, as for instance, wall 6, is provided a threaded aperture 8 designed to receive a set screw 9. Preferably this set screw is of 45 less length than the aperture 8 so that when it is tightened as shown in Figure 3, the end will be countersunk.

When the quoin is not in use, the screw 50 9 is usually loose so that the quoin may slide on its co-acting quoin or be readily removed therefrom. However, after the quoins have been assembled as shown in Figure 1 and a wrench used for shifting the quoins to a desired position, the screw 9 in each of the 55 quoins is tightened whereby the respective

quoins are locked against accidental shifting. If desired, one screw may be tightened and the other left loose, though ordinarily both screws would be tightened in order to insure against any accidental displacement. In 60 order to assist the action of the screws, the respective beads 5 are each provided with a roughened or corrugated surface 10 on each side.

In Figure 4, a slightly modified construction is shown wherein an auxiliary screw 9' is provided and arranged preferably diametrically opposite screw 9 though it could be offset if desired. By reason of the use of two screws, either side of the quoin could 65 be left uppermost and preferably actuated to lock the quoins together.

In Figure 5, a further modified form of the invention is shown wherein the quoins 1' and 2' are formed identical and each is 70 formed at its large end with a notch or cut out portion 11 which is almost filled by a clamping member 12, which clamping member is a substantially U-shaped structure 75 and provided with a stem 13 extending 80 through a suitable bore 14 so that the end 15 may be riveted or offset. The body or U-shaped part of the clamping member 12 is provided with a comparatively narrow 85 slit or opening 16 and a wider opening 17 85 for receiving the tongue 5 of the adjacent quoin. By this construction and arrangement, whenever the screw 9 and 9' are tightened, the arms of the clamping member 12 will be pressed against the sides of 90 the tongue 5 and thereby lock the two quoins together. A locking action will be, of course, provided if one of the screws is tightened, though ordinarily, it is preferable to tighten both screws.

95 What I claim is:

1. In a device of the character described, a pair of quoins, each quoin being provided with a groove and a tongue, the tongue of one quoin fitting into the groove of the opposite quoin, a substantially U-shaped clamping member carried by one of the quoins, said U-shaped clamping member being fitted into said grooves, and means for causing said clamping member to grip the 100 tongue of the other quoin.

2. In a device of the character described, a pair of quoins, each quoin being provided with a groove and a tongue, the tongue of one quoin fitting into the groove of the op- 105 110

posite quoins, a substantially U-shaped clamping member arranged in each of said grooves, and means acting at right angles to the tongues of the quoins for causing the respective clamping members to grip said tongues.

3. In a device of the character described, a quoins provided with a tongue and a groove at one end, a substantially U-shaped clamping member arranged in said groove, said clamping member having a retaining stem projecting through the body of the quoins, and a set screw arranged on each side of said clamping member, said set screws being positioned to force said clamping mem-

ber into said groove from opposite sides into clamping position.

4. A quoins provided with a tongue and a groove at one end arranged in line with and above the tongue so as to receive the bead of another quoins, the walls of the quoins on opposite sides of the groove being formed with threaded apertures extending entirely therethrough, and a set screw arranged in each of the threaded apertures, 25 said set screws being wholly within the apertures and adapted to be forced into the groove for pinching the tongue of the co-acting quoins.

JAMES J. CURTIS.
